UNITED STATES PATENT OFFICE.

EDWARD L. HEDEMARK, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR AN ESCUTCHEON PLATE FOR A RADIORECEIVER.

Application filed August 7, 1926. Serial No. 18,632. Term of patent 7 years.

To all whom it may concern:

Be it known that I, EDWARD L. HEDEMARK, a citizen of the United States, residing in the city of Chicago, in the county of Cook and State of Illinois, have invented a new, original, and ornamental Design for Escutcheon Plate for a Radioreceiver, of which the following is a specification, reference being had to the accompanying drawings, forming a part thereof.

The drawing is a front face view slightly

in perspective, showing the escutcheon plate for a radio receiver embodying my new design.

I claim:—

The ornamental design for an escutcheon plate for a radioreceiver, substantially as shown.

In testimony whereof, I have hereunto set my hand this 30 day of July, 1926.

EDWARD L. HEDEMARK.
